UNITED STATES PATENT OFFICE.

JOHN P. WIENS, OF MILWAUKEE, WISCONSIN.

BRUSH.

No. 821,968.

Specification of Letters Patent.

Patented May 29, 1906.

Application filed December 18, 1901. Serial No. 86,361.

To all whom it may concern:

Be it known that I, JOHN P. WIENS, residing at Milwaukee, in the county of Milwaukee and State of Wisconsin, have invented 5 a new and useful Improvement in Brushes, of which the following is a description, reference being had to the accompanying drawings, which are a part of this specification.

My invention has relation to improvements in that class of brushes commonly known as "dustless" sweeping-brushes in which a series of absorbent tufts are bordered by non-absorbent tufts, the absorbent tufts adapted to have a more or less volatile oil, 15 such as kerosene or gasolene, fed thereto.

One of the primary objects of my present invention is to provide a cover for the back stamped from a single sheet of metal and bulged upwardly to form an oil-chamber between said cover and the back and also advisably having side flanges extending downwardly against the sides and ends of the brush-back and preferably beneath said back for a short distance.

It is an advantage to provide but a single back-piece for a brush and at the same time provide for all the tufts being composed of long material doubled centrally and the butts thereby formed inserted into openings extending through said single back-piece, which openings lead from the interior of the recess or cavity, and held in place by being wiredrawn, but yet at the same time the arrangement must be such that the non-absorbent tufts will not be exposed to the oil in the recess or cavity of the back.

Another important object, therefore, of my invention is to secure this desirable result.

With the above primary and other incidental objects in view the invention consists of the devices and parts or their equivalents, as hereinafter set forth.

In the accompanying drawings, Figure 1 is an elevation of a brush embodying my improvements. Fig. 2 is a plan view with the handle removed and a portion of the top broken away. Fig. 3 is a cross-sectional view on the line 3-3 of Fig. 1, and Fig. 4 is a 45 detail fragmentary view of the handle looking on the under side thereof, and Fig. 5 is a 50 transverse section of the brush with the cover removed.

Referring to the drawings, the numeral 7 55 indicates a brush-back provided with a series of openings therethrough, said openings pref-

erably arranged in series of longitudinal lines. One or more of these lines of openings may be utilized for securing therein the absorbent tufts, and the remaining openings are utilized for securing therein the non-absorbent tufts. In the drawings I have shown the central line of openings (designated by the numeral 8) as the openings in which the absorbent tufts 9 are secured and the remaining lines of openings (designated by the numeral 10) as the openings in which the non-absorbent tufts 11 are secured. The absorbent tufts 9 are preferably of palma fiber or other suitable absorbent material of sufficient length to enable them to be doubled or folded centrally and the butts thereby formed inserted into the openings, and the non-absorbent tufts 11 are of Tampico fiber or other suitable non-absorbent material of sufficient length to permit them to be also doubled or bent centrally and the butts thereby formed inserted in the openings. The butts of the fibers referred to are passed upwardly in the openings sufficiently far to enable wires 12 to be inserted through the loops formed at the bend of the fibers, the said wire being drawn tight, so that the fibers are securely held in place. Now as the top of the brush-back forms the bottom of the oil recess or cavity and as said oil should only feed down through the openings 8, in which the absorbent tufts are secured, it is necessary that the openings 10, in which the non-absorbent tufts are secured, should be 75 made impervious to the feed of oil therethrough and onto the non-absorbent tufts. My invention therefore contemplates plugging up the said openings, and this may be accomplished in any desirable manner, although I prefer to do this by applying a suitable oil-proof cement 13 in the openings 10 and over the butts of the non-absorbent tufts, forming plastic plugs, as most clearly shown in Figs. 2, 3, and 5. This cement is 80 also applied over the entire top of the brush, whereby said top, which is of wood, is rendered impervious to the escape of the oil except through the central line of openings 8, in which the butts of the absorbent tufts are 85 secured, whereby the oil is free to enter only said line of openings 8 and feed down the absorbent tufts, the said oil preventing the rising of dust, and thereby avoiding a disagreeable feature inherent in the ordinary form of 90 brushes in which the dustless feature is absent.

By my improved construction as thus far described I am enabled to secure the tufts in the most advantageous manner—*i. e.*, by passing the butts thereof through openings 5 and securing the same by wire drawn through the loops and over the upper side of the back of the brush, and yet at the same time I guard effectually against the escape of the oil from the recess or cavity through the openings in 10 which the butts of the non-absorbent tufts are secured. Another important feature of my invention is the provision of an improved form of top or cover for the brush-back, said top or cover being formed from a single sheet 15 of metal stamped out to the required shape. This top piece or cover is indicated by the numeral 14 and is provided longitudinally with an outwardly-bulged portion, which forms between its under side and the top of the 20 brush-back an interior chamber 15 of considerable width and capacity. At its side and end edges the top or cover is flanged outwardly to form the flat surfaces 16, which rest squarely upon the upper side of the 25 brush-back. I prefer, however, to flange the metal downwardly along the side and end edges of the brush-back, as indicated by the numeral 17, whereby the edges of the wooden back are prevented from wear by contact 30 with hard objects in the operation of sweeping. If desired, also, in order to assist in securing the top or cover firmly in place the lower edges of said top or cover are bent under the brush-back for a short distance, as 35 clearly shown in Figs. 1 and 3 and as indicated by the numeral 18.

The handle of the device is indicated by the numeral 19, and the inner end 20 of said handle, which is shown as a socket to receive 40 the handle proper, is formed with a flat portion 21, said flat portion provided on its under side with intersecting or crossed grooves 22 22, which, at the center or crossing-point, merge into a central opening 23. On the 45 outer side of the top or cover are intersecting or crossed ribs 24 24, which at the intersecting or crossing point are interrupted by an opening 25. The metal of the top or cover where these ribs are provided is advisably reinforced, so that said top or cover may have 50 sufficient strength to resist the strain which is exerted at this point. In adjusting the handle to the top or cover two of the grooves of said handle are made to fit two of the ribs 55 of the top piece. A bolt 26 is then passed through the registering openings 23 and 25, the head of the bolt being against the under side of the top piece, and a winged nut 27 is turned onto the upper threaded end of the 60 bolt in order to securely clamp the handle to the top or cover. In the drawings the handle is secured so as to extend out at right angles to the length of the brush. If it is desired to shift the position of the handle, so as 65 to extend out at right angles from the opposite

side of the brush, all that is necessary to be done is to loosen the winged nut, turn the handle around to the position referred to, taking care that the grooves and ribs engage with each other, and then again tighten the 70 winged nut, or, again, if it is desired that the handle should project in the direction of the length of the brush said handle can be swung around so as to extend out from either end and secured in such position by tightening the 75 winged nut.

It will be noticed, particularly from Fig. 3, that the oil-proof cement is also disposed between the inner sides of the flanges 17 of the top or cover and the outer edges of the brush-back, whereby the oil is prevented from leaking therebetween and at the same time air-tight joints are provided. 80

For introducing the oil into the chamber 15 I provide the top or cover with an opening, 85 in which is fitted a tube 33, the upper edge of said tube being flanged outwardly. The interior of the tube is threaded, and engaging these threads is a depending stem from a cap 34. When the stem is turned into the tube, 90 the cap is adapted to be brought into engagement with the flanged upper end of said tube, and thereby close the opening. A packing 35 is advisably interposed between this flange and the under side of the cap. When it is 95 desired to fill the oil recess or cavity with oil, the cap is removed and said oil poured through the opening of the top or cover 14.

What I claim as my invention is—

1. In a brush, the combination of a brush-back provided on its upper side with an oil-chamber and having a series of openings extending from its under side upwardly, all of said openings leading into the oil-chamber, absorbent and non-absorbent tufts extending from and secured in the openings, and means plugging up the upper ends of the openings in which the non-absorbent tufts are secured so as to permit the oil to pass from the oil-chamber only through the openings in which the absorbent tufts are secured and onto said absorbent tufts. 100

2. In a brush, the combination of a brush-back provided on its upper side with an oil-chamber and having a series of openings extending from its under side upwardly, all of said openings leading into the oil-chamber, absorbent and non-absorbent tufts extending from and secured in the openings, an oil-proof cement coated over the bottom of the 105 oil-chamber and filling in the upper ends of the openings in which the non-absorbent tufts are secured so as to permit the oil to pass from the oil-chamber only through the openings in which the absorbent tufts are secured, and onto said tufts, and means for 110 supplying oil to said oil-chamber. 120

3. In a brush, the combination of a brush-back formed or provided with a series of openings extending therethrough, and also pro- 125 130

vided on its upper side with an oil-chamber into which the openings extend, absorbent and non-absorbent tufts doubled over medially with the bends thereof inserted into the 5 openings, wires extending over the upper side of the brush-back and inserted through the loops formed by the bends or doubled-over portions of the tufts, means plugging up the upper ends of the openings in which the 10 non-absorbent tufts are secured, so as to permit the oil to pass from the oil-chamber only through the openings in which the absorbent tufts are secured and onto said absorbent tufts, and means for supplying oil to the oil-chamber. 15

4. In a brush, the combination of a wooden brush-back formed or provided with a series of openings extending therethrough, an upwardly-bulged, open-bottom metallic top or 20 cover secured over the upper side of the brush-back, and forming an oil-chamber between it and said upper side of the brush-back, and into which chamber the openings of the brush-back extend, absorbent and 25 non-absorbent tufts extending from and secured in the openings, an oil-proof coating over the upper side of the wooden brush-back and filling in the upper ends of the openings in which the non-absorbent tufts are 30 secured, so as to permit the oil to pass from the oil-chamber only through the openings in which the absorbent tufts are secured and onto said absorbent tufts, and means for supplying oil to the oil-chamber. 35

5. In a brush, the combination of a brush-back provided on its upper side with a liquid-chamber and having a series of perforations extending entirely therethrough and opening into the liquid-chamber, tufts seated in the

said perforations, and impervious plugs inserted in some of the perforations. 40

6. In a brush, the combination of a brush-back provided on its upper side with a liquid-chamber and having a series of perforations extending entirely therethrough and opening 45 into the liquid-chamber, tufts seated in the said perforations and plastic impervious plugs inserted in some of the perforations.

7. In a brush, the combination of a brush-back provided on its upper side with a liquid-chamber and having a series of perforations extending entirely therethrough and opening 50 into the liquid-chamber, tufts seated in the said perforations, and a plastic impervious coating applied over the brush-back and filling in some of the perforations. 55

8. In a brush, the combination of a brush-back, a top or cover secured to the brush-back and forming a chamber therewith, said brush-back having perforations extending 60 entirely therethrough and opening into the chamber, tufts secured in the perforations, and means within the chamber for plugging some of the perforations.

9. In a brush, the combination of a brush-back, an oil-chamber carried thereby, said oil-chamber having the back of the brush for its bottom, said brush-back having tuft-openings extending entirely therethrough, tufts seated in the tuft-openings, and a coating of 65 cement on the bottom of the oil-chamber closing some of the tuft-openings. 70

In testimony whereof I affix my signature in presence of two witnesses.

JOHN P. WIENS.
